CLAIM

The ornamental design for a medical dressing as shown and described.

DESCRIPTION

FIG. 1 is a perspective view of a medical dressing showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

In the drawings, same sized broken lines of the medical dressing in FIGS. 1 and 2 do not form portions of the claimed design.

In the drawings, dash-dot-dot lines are boundary lines to the claimed design.

In the drawings, the shaded areas shown in FIGS. 1, 2, 6, and 7 form portions of the claimed design.

Color does not form part of the claimed design for the embodiments shown in FIGS. 1-7.
